HEATER HOUSING FOR HAIR ROLLERS AND STEAM VAPORIZERS

Samuel J. Popeil, 2920 N. Commonwealth Ave.,
Chicago, Ill. 60607

Filed July 26, 1967, Ser. No. 8,004

Term of patent 14 years

(Cl. D23—77)

FIG. 1.

FIG. 2.

FIG. 3.

FIG. 4.

FIG. 5.

FIGURE 1 is a front perspective view of a heater housing for hair rollers and steam vaporizers showing my new design.

FIGURE 2 is a front elevational view thereof.

FIGURE 3 is a top view of the steam chest as shown in FIGURE 2.

FIGURE 4 is a rear view.

FIGURE 5 is an end view, each end being a mirror image of the other end.

I claim:

The ornamental design for a heater housing for hair rollers and steam vaporizers, as shown and described.
